UNITED STATES PATENT OFFICE.

GLENN COLE, OF CHICAGO, ILLINOIS, ASSIGNOR TO THE REECE BUTTON HOLE MACHINE COMPANY, OF BOSTON, MASSACHUSETTS, A CORPORATION OF MAINE.

THREAD CUTTING AND CLAMPING DEVICE FOR SEWING-MACHINES.

1,197,797.

Specification of Letters Patent. Patented Sept. 12, 1916.

Application filed March 17, 1915. Serial No. 15,025.

To all whom it may concern:

Be it known that I, GLENN COLE, a citizen of the United States, residing at Chicago, county of Cook, State of Illinois, have 5 invented an Improvement in Thread Cutting and Clamping Devices for Sewing-Machines, of which the following description, in connection with the accompanying drawing is a specification, like characters on the 10 drawing representing like parts.

This invention relates to sewing machines and has for its object to provide a novel device for cutting the needle thread at the end of the stitching operation and for clamping 15 the end of the thread leading to the source of supply until the stitching operation is started again thereby relieving the operator of this duty and insuring the correct formation of the first stitches when the machine is 20 started.

While my invention is capable of use in connection with sewing machines of different types, I have chosen herein to illustrate it as it would be employed in a buttonhole sewing machine of the well-known "Reece" type, examples of which are shown in the following United States patents: No. 494,280, March 28, 1893; No. 655,637, August 7, 1900; No. 1,030,589, June 25th, 1912. 25 Buttonhole sewing machines of this type are provided with work-clamping means and stitch-forming mechanism which have a movement relative to each other not only to give the work a relative feeding movement 30 during the stitching on the buttonhole, but also to move the parts from buttonhole-cutting position to stitching position before the stitching operation on the buttonhole begins and then to return the parts to button- 35 hole-cutting position from stitching position after the buttonhole has been completed. Said machines are also provided with a buttonhole-cutting device which operates to cut the buttonhole either before or 40 after the stitching operation and when the parts are in buttonhole-cutting position. The construction of machines such as illustrated in the above-mentioned patents is 45 such that the machine is brought to rest at the end of a predetermined cycle of operations with the parts in buttonhole-cutting position, and when the machine is started the work-clamping means and stitch-forming mechanism are given a relative movement 50 to bring them from buttonhole-cutting

position into stitching position, at which time the stitch-forming mechanism is set in operation to concatenate the edge stitches of the buttonhole. During the stitching operation, the work-clamping means and 60 stitch-forming mechanism have a relative feeding movement to provide for laying the stitches around the edge of the buttonhole, and when the stitching operation on the buttonhole has been completed, the stitch-forming mechanism is brought to rest and the work-clamping means and stitch-forming mechanism have a further final relative movement to bring them into their initial position, during which final movement the 70 work is automatically unclamped. The buttonhole-cutting mechanism operates to cut the buttonhole when the parts are in their buttonhole-cutting position and either before or after the stitching operation. 75

My present invention comprehends a novel thread-clamping device which is rendered operative automatically by the relative movement of the stitch frame and work-clamping means to clamp the needle thread above the work after the stitching operation has been completed on a buttonhole and during the final relative movement of the stitch-forming mechanism and work-clamping means by which they are brought from 80 stitching position into buttonhole-cutting position and to hold the end of the needle thread firmly clamped until the machine has been started for stitching the next succeeding buttonhole and the initial stitches are 85 being formed, after which the thread is automatically released. Associated with the thread clamp is a thread cutter by which the needle thread is cut after it has been clamped. 90

In my improved device the clamping of 95 the needle thread is accomplished while the stitch-forming mechanism and work-holding means have one position relative to each other, that is, while they are moving from their stitching to buttonhole-cutting position, and the unclamping of the needle thread is accomplished while they have another position relative to each other, that is, while they are in stitching position. The means which I have herein illustrated for 100 actuating the thread-clamping device by the relative movement between the stitch frame and clamp frame is such as to cause the needle thread to be clamped when the stitch frame and clamp frame have one po- 105 110

sition relative to each other and to cause the needle thread to be unclamped when they have another position relative to each other.

5 In order to give an understanding of my invention, I have illustrated in the drawings a selected embodiment thereof which will now be described, after which the novel features will be pointed out in the appended 10 claims.

10 Figure 1 of the drawings is a side view of a portion of a buttonhole-stitching machine of the "Reece" type having my improvements applied thereto; Fig. 2 is a plan view 15 of Fig. 1 with a portion of the overhanging arm of the stitch frame broken out; Fig. 3 is an enlarged side view of my improved thread cutter and clamp showing the parts in different positions; Fig. 4 is a section on 20 the line α — α , Fig. 2; Figs. 5, 6, 7, 8 and 9 are fragmentary detail views of the clamp- 25 actuating member showing the parts in different positions.

In the sewing machine herein illustrated, 30 the stitch-forming mechanism is supported on a so-called stitch frame 1, and it comprises the usual upper and under thread-handling mechanism which coöperate to concatenate the edge stitches of the buttonhole. The under thread-handling mechanism is not herein illustrated, but is of the usual construction found in buttonhole sewing machines of the "Reece" type. The upper thread-handling mechanism is shown 35 as comprising an eye-pointed needle 4 carried by the usual needle bar 3 which reciprocates in bearings in an overhanging arm 2 formed on the stitch frame 1. The work-clamping means is herein shown as the usual 40 work clamps 5 carried by arms 6 that are pivoted at 80 to a frame 7 hereinafter referred to as the clamp frame, all as usual in buttonhole sewing machines of the above-mentioned type. The parts are shown in 45 full lines in Fig. 1 in buttonhole-cutting position, that is, in the position they occupy when the machine has been brought to rest at the end of the stitching operation on a buttonhole, and as is well known to 50 those familiar with buttonhole sewing machines of this type, when the machine is started the work clamps 5 are first operated to clamp the work in position and the cutter 90 is operated to cut the buttonhole. The 55 stitch frame 1 and clamp frame 7 then have a relative movement to bring the needle into the dotted line position, Fig. 1, at which time the stitching mechanism is set in operation to begin the stitching of the buttonhole. During the stitching of the buttonhole, the stitch frame and clamp frame have a relative movement to insure the proper feeding of the work, and the stitch-forming mechanism also has a turning movement to 60 enable the stitches to be formed around the 65

ends of the buttonhole, and after the buttonhole has been completed, the stitch frame 1 and clamp frame 7 have a further relative movement to bring the parts into the relative position shown in Fig. 1, during which movement the work is unclamped automatically and the clamps 5 are raised. When the stitching on any buttonhole has been completed, the stitch frame has such a position 70 that the needle and needle bar occupy approximately the dotted line position, Fig. 1, and the final relative movement between the stitch frame and clamp frame by which they are carried from stitching position to buttonhole-cutting position, results in carrying 80 the needle and needle bar from the dotted to the full line position, Fig. 1.

Inasmuch as the operation of a buttonhole sewing machine of the above type is well known to those skilled in the art, it is not 85 necessary to further describe its construction or operation.

As stated above, I have provided herein a novel thread clamp which is rendered operative automatically by the relative movement 90 between the stitch frame and clamp frame to grip or clamp the needle thread after the stitching operation is completed on any buttonhole and while the stitch frame and clamp frame are having their final relative movement from stitching position to buttonhole-cutting position, which thread clamp holds the end of the needle thread leading to the needle until the stitch-forming mechanism and work-holding means are again carried into stitching position relative to each other and the stitching has commenced on the next succeeding buttonhole thereby insuring that when the stitching operation is begun the first stitch will be properly 105 formed without danger that the end of the needle thread will be drawn through the work when the needle loop is being formed during the first stitch.

My improved thread-clamping device is 110 rendered operative to clamp the thread when the stitch-forming mechanism and work clamps are in one position relative to each other and to release the thread when they are in another position relative to each other.

My improved thread-clamping device is 115 herein shown as carried by the work-clamping mechanism and it is illustrated as comprising two relatively movable clamping 120 jaws 8 and 9 carried by two arms 10 and 11, respectively. The arm 10 is fixedly mounted to one of the arms 6 of the work-clamping mechanism in some suitable way, as by means of a screw 13, and the arm 11 is shown as pivotally mounted to the arm 10, as at 12, said arm 11 having a slot 14 therein in which operates a pin 15 carried by the arm 10, said slot operating to limit the swinging movement of the arm 11. The clamping jaw 8 is 130

thus a stationary jaw, and the clamping jaw 9 is a movable jaw. Means are provided for closing the jaws together when the stitch frame and clamp frame are moving 5 from stitching to buttonhole-cutting position, and these clamping jaws are so positioned that during such relative movement the needle thread t will be drawn between them. The closing of the jaws thus clamps 10 the needle thread. Said means are also constructed so that they will hold the jaws closed until after the stitch-forming mechanism and work-holding means move from buttonhole-cutting into stitching position 15 when the machine is again started, said means operating to permit the jaws to open to release the thread just as the initial stitches are formed on the next succeeding buttonhole. These means, therefore, close 20 the thread-clamping jaws to clamp the thread when the stitch-forming mechanism and work-clamping means are in one position relative to each other and permit the jaws to open to release the thread when they 25 are in another position relative to each other. In the illustrated embodiment of my invention the jaws are normally held open by a spring 25 which is secured to an arm 23 extending from the arm 11. For 30 closing the jaws at the proper time and for holding them closed until the needle thread is to be released, I have herein provided a clamp-actuating member 16 which is secured to the stitch frame and co-operates 35 with the arm 11 as the stitch frame and clamp frame have their relative movement to move the jaw 9 against the jaw 8. This clamp-actuating member 16 is shown as adjustably secured to a bracket 17 by means of 40 two screws 19 which extend through a slot 20 formed in the end of the member 16, and the bracket is secured to the stitch frame by a screw 18, this construction providing for any necessary adjustment of said 45 clamp-actuating member. The clamp-actuating member 16 is preferably somewhat resilient, and it is formed at its end with a cam portion 21 and with a projection or extension 22 below the cam portion. This 50 cam portion 21 and extension 22 co-operate with the downwardly-extending portion 24 of the finger 23 which extends laterally from the arm 11 carrying the movable clamping jaw 9, thereby to clamp the needle 55 thread t and to release the latter at the proper times in the cycle of operations.

As stated above, the parts are shown in Figs. 1 and 5 in the positions they assume when the machine has been brought to rest 60 at the end of the stitching operation on a buttonhole, and it will be noted that the portion 24 of the finger is engaged by the cam portion 21 of the clamp-actuating member 16 and is above the extension 22. When 65 the machine is started the work clamps 5

are first depressed to clamp the work in position and the stitch frame and clamp frame are moved relative to each other to bring the needle 4 into the dotted line position, Fig. 1, at which time the stitching operation begins. When the stitching on the buttonhole has been completed the needle occupies substantially the dotted line position, Fig. 1, and the work clamps 5 are still depressed. During the stitching operation the thread-clamping jaws 8 and 9 are separated from each other, as shown in dotted lines Fig. 2, this being accomplished by means of the spring 25, as above described.

The work clamps 5 are released automatically at the termination of the stitching operation and while the needle is in approximately the dotted line position Fig. 1, and this releasing movement of the clamps brings the portion 24 of the finger 23 into line with 80 the cam 21 of the clamp-actuating member. When the stitch frame and clamp frame have their final relative movement to carry the needle from the dotted to the full line position, Fig. 1, the needle thread is carried 85 between the two jaws 8 and 9, which it will be understood are separated from each other by the action of the spring 25. This relative movement of the stitch frame and clamp frame also causes the clamp-actuating member 16 to move relative to the finger 23, thus 90 bringing the cam 21 into engagement with the portion 24 of the finger, as shown in Figs. 1 and 5. The action of the cam 21 on the finger 24 is to force yieldingly the arm 11 laterally, thereby closing the clamping jaw 9 against the clamping jaw 8. This 95 operation, as stated above, occurs after the stitch frame and clamp frame have had sufficient relative movement to bring the 100 needle thread t between the clamping jaws so that the action of the cam 21 on the portion 24 results in clamping the portion of the needle thread between the needle and the work between the two clamping jaws 8 and 9. When the machine comes to rest in the full line position, Fig. 1, the needle 105 thread is thus clamped between the jaws 8 and 9 and is held clamped by the action of the member 16 on the extension 24 of the 110 finger 23.

When the machine is set in operation for sewing the next succeeding buttonhole the work clamps 5 are first depressed, thus carrying the portion 24 of the finger 23 downwardly into the position shown in Fig. 6. This movement does not, however, release 120 the thread clamps 8 and 9 because the portion 22 of the member 16 is still in engagement with the downwardly-turned end 24 of the finger 23. After the thread is clamped the stitch frame and clamp frame have a relative movement before the stitching operation begins to bring the needle into the relative position shown in dotted lines Fig. 130

1, and during this movement the downwardly-extending portion 24 of the finger 23 is in engagement with the inner face of the extension 22 of the member 16, as shown 5 in full lines Figs. 2 and 3. At the time that the stitching operation begins the parts are in approximately the position shown in Figs. 2 and 3 and the end of the needle thread is still clamped between the jaws 8 10 and 9 so that when the first stitch on the buttonhole is formed the end of the needle thread will be firmly held in the thread clamp to insure the correct formation of the first stitch. As the stitching operation proceeds 15 the stitch frame and clamp frame have a relative feeding movement to stitch down one side of the buttonhole, and during this movement the extension 22 is withdrawn from the portion 24 of the finger 23, as shown 20 in Fig. 7. The disengagement of these parts, however, does not actually take place until after the first stitch has been formed. As soon as the extension 22 has been withdrawn from the portion 24 of the finger 23, the spring 25 acts automatically to open the thread-clamping jaws thereby to release the end of the needle thread, but as stated above, this does not occur until after the first stitch at least has been formed. 25 During the further operation of stitching the buttonhole, the stitch frame and clamp frame have a relative movement to still further withdraw the member 16 from the finger 23 as the stitching is carried down 30 one side of the buttonhole. When the stitching is carried around the end of the buttonhole and up the other side, the member 16 will be moving toward the finger 23, but as the thread-clamping jaws are opened the portion 24 of the finger 23 occupies the dotted line position in Fig. 2. As a result, the projection 22 of the member 16 will pass in 35 behind the portion 24 of the finger 23. When the stitching operation is completed the relative movement between the stitch frame and clamp frame has brought the parts into substantially the position shown 40 in Fig. 8. At this time the work is unclamped automatically and the raising of the clamps 5 and their arm 6 carries the portion 24 of the finger 23 upwardly in front of the cam 21 as shown in Fig. 9. At this time the clamping jaws 8 and 9 are opened and in position to receive the needle thread 45 between them when the stitch frame and clamp frame have their final relative movement to carry them into the relative position shown in full lines Fig. 1. During this relative movement the cam 21 engages the portion 24 of the finger 23 and forces the arm 11 laterally thereby shutting the clamping jaw 9 against the jaw 8 and clamping 50 the needle thread as above described.

It will thus be seen that I have provided 65 a thread-clamping device which is rendered

operative by the relative movement of the work-clamping means and stitch-forming mechanism to clamp automatically the needle thread at the end of the stitching operation and to release said needle thread 70 when the stitching has begun on the next succeeding buttonhole. It will also be seen that the device herein illustrated is so constructed that the clamping of the needle thread is accomplished when the stitch-forming mechanism and work-clamping means are in one position relative to each other while the release of the needle thread is accomplished while they are in another position relative to each other. With my 80 device the operator is relieved entirely of the duty of holding the end of the needle thread when the stitching operation is commenced.

Associated with my thread-clamping device is a thread cutter by which the needle thread is automatically severed. This thread cutter is shown as a blade 26 fastened to the underside of the clamping jaw 8. The thread is cut by the operation of shifting the work into position to have a fresh buttonhole stitched. When a buttonhole is completed and the needle thread has been clamped, as above described, the needle thread extends from the clamp directly to 90 the work. After the work has been unclamped the operator shifts it laterally into correct position to have the next buttonhole stitched, and this lateral shifting movement of the work brings the needle thread 95 against the edge of the cutter 26, as shown by the dotted lines Fig. 4, thus automatically severing the needle thread.

While I have illustrated herein a selected embodiment of my invention, I do not wish 105 to be limited to the constructional features shown. Further, I wish to state that while the invention is shown as applied to a buttonhole sewing machine of the "Reece" type, yet it is equally applicable to other 110 types of sewing machines.

I claim:

1. In a sewing machine, the combination with stitch-forming mechanism, of work-clamping means situated above the work, 115 said stitch-forming mechanism and work-clamping means having a movement relative to each other in a direction parallel to the work held by said work-clamping means to effect a predetermined cycle of 120 operations including a stitching operation, a thread-clamping device carried by the work-clamping means, and means rendered operative by said relative movement to cause the thread-clamping device to clamp 125 the thread at the end of the stitching operation.

2. In a sewing machine, the combination with stitch-forming mechanism, of work-clamping means situated above the work, 130

- said stitch-forming mechanism and work-clamping means having a movement relative to each other in a direction parallel to the work held by said work-clamping 5 means to effect a predetermined cycle of operations including a stitching operation, a thread-clamping device carried by the work-clamping means, and means rendered operative by said relative movement to 10 cause the thread-clamping device to clamp the thread at the end of the stitching operation and to release the thread immediately after the formation of the initial stitches of the next succeeding stitching operation. 15 3. In a buttonhole sewing machine, the combination with stitch-forming mechanism, of work-clamping means situated above the work, said stitch-forming mechanism and work-clamping means having a 20 movement relative to each other during which the stitching around a buttonhole is performed, thread-clamping jaws carried by the work-clamping means, and a clamp-actuating member secured to the stitch 25 frame and adapted to actuate said jaws to clamp the thread therebetween during such relative movement at the end of a stitching operation on a buttonhole. 4. In a sewing machine, the combination 30 with stitch-forming mechanism, of work-clamping means situated above the work, said stitch-forming mechanism and work-clamping means having during each cycle of operations a movement relative to each other both during and after a predetermined stitching operation, a thread-clamping device carried by the work-clamping means, and means rendered operative by said relative movement to cause the thread-clamping 40 device to clamp the thread at the end of the stitching operation when the stitch-forming mechanism and work-clamping means are in one position relative to each other and to release the thread as the initial stitches of the next succeeding stitching operation are being formed and when the stitch-forming mechanism and work-clamping means are in another position relative to each other. 45 5. In a sewing machine, the combination 50 with a stitch frame carrying stitch-forming mechanism, of a clamp frame, said frames having a movement relative to each other, a work-clamping member carried by the clamp frame and movable relative thereto into and out of operative position to clamp and unclamp the work, thread-clamping means carried by said work-clamping member, and means rendered operative by the relative movement of the frames to clamp the thread in said thread-clamping member at the end of the stitching operation. 60 6. In a sewing machine, the combination 65 with a stitch frame carrying stitch-forming mechanism by which predetermined stitching operations are performed, of a clamp frame, said frames having a movement relative to each other both during and after each stitching operation, a work-clamping member carried by the clamp frame and movable relative thereto into and out of operative position to clamp and unclamp the work, thread-clamping means carried by said work-clamping member, and means rendered operative by the relative movement of the frames to clamp the thread in said thread-clamping member at the end of the stitching operation and to release the thread immediately after the formation of the initial stitches of the next succeeding stitching operation. 70 7. In a sewing machine, the combination with a stitch frame carrying stitch-forming mechanism, of a clamp frame, said frames having a movement relative to each other, a work clamp carried by said clamp frame, 75 two thread-clamping jaws both secured to the work clamp and capable of movement relative to each other, and a clamp-actuating member secured to the stitch frame, relative movement of said frames causing the clamp-actuating member to move the thread-clamping jaws relative to each other to clamp the thread therebetween at the end of the stitching operation. 80 8. In a sewing machine, the combination 85 with a stitch frame carrying stitch-forming mechanism, of a clamp frame, said frames having a movement relative to each other, a work clamp carried by said clamp frame, thread-clamping jaws secured to the work 90 clamp, and a clamp-actuating member secured to the stitch frame, relative movement of said frames causing the clamp-actuating member to move the thread-clamping jaws relative to each other to clamp the thread therebetween at the end of the stitching operation and to release the thread immediately after the formation of the initial 95 stitches when the machine is again set in operation. 100 9. In a buttonhole sewing machine, the combination with a stitch frame carrying stitch-forming mechanism, of a clamp frame, said frames having a movement relative to each other, work clamps pivotally mounted to the clamp frame, thread-clamping jaws secured to the work clamps, one of said jaws having a projection associated therewith, and a clamp-actuating member secured to the stitch frame and provided with means which is brought into engagement with said projection during said relative movement at the end of the stitching operation thereby to clamp the thread between said jaws and to maintain operative engagement with said projection during the further movement of the frames and until the initial stitches have been formed at the beginning of the stitching operation. 115 10. In a sewing machine, the combination 120 125 130

with a stitch frame carrying stitch-forming mechanism, of a clamp frame, a work clamp pivotally mounted to said clamp frame, thread-clamping jaws carried by the work 5 clamp, one of said jaws having a projection, a clamp-actuating member secured to the stitch frame and provided with a cam portion situated to engage said projection when the work clamp is opened and at the end of 10 the stitching operation thereby to clamp the thread and also provided with an extension which acts on said projection to hold the thread clamped after the work clamp is in operative engagement with the work and 15 until the initial stitches are formed at the beginning of the next stitching operation.

11. In a sewing machine, the combination with a stitch frame carrying stitch-forming mechanism, of a clamp frame carrying work- 20 clamping means, said stitch frame and clamp frame having a movement relative to each other in a direction parallel to the work held by the work-clamping means, a thread-clamping device carried by the work-clamp- 25 ing means above the work, means actuated by the relative movement of said frames to cause said thread-clamping device to clamp the thread at the end of the stitching operation, and a thread-cutting device associated 30 with said thread-clamping device.

12. In a buttonhole sewing machine, the combination with a stitch frame carrying stitch-forming mechanism, of a clamp frame carrying work-clamping means, thread- 35 clamping jaws carried by the work-clamping means above the work, a clamp-actuating member secured to the stitch frame and operating through the relative movement of said frames to actuate said jaws to clamp 40 the thread therebetween at the end of a stitching operation on a buttonhole and to release said thread after the initial stitches have been formed on the next succeeding buttonhole, and a thread-cutter associated 45 with one of said thread-clamping jaws.

13. In a buttonhole sewing machine, the combination with stitch-forming mechanism, of work-clamping means situated above the work, said stitch-forming mechanism and work-clamping means having a 50 relative movement during which the edge stitches of a buttonhole are formed and the parts are moved from stitching position to buttonhole-cutting position, and means carried by said work-clamping means and actuated by said relative movement to clamp the thread at the end of a stitching operation when the stitch-forming mechanism and work-clamping means are in one position 55 relative to each other and to release said 60

thread as the initial stitches of the next succeeding stitching operation are being formed and when the stitch-forming mechanism and work-clamping means are in another position relative to each other. 65

14. In a buttonhole sewing machine, the combination with stitch-forming mechanism, of work-clamping means situated above the work, said stitch-forming mechanism and work-clamping means having a relative 70 movement during which the edge stitches on a buttonhole are formed and the parts are moved from stitching position to buttonhole-cutting position, a pair of thread-clamping jaws carried by the work-clamp- 75 ing means above the work and situated so that the needle thread is carried between them during the relative movement of said stitch-forming mechanism and work-clamping means from stitching to buttonhole-cutting position, and means actuated by 80 said relative movement to close said jaws thereby to clamp the needle thread and to release said jaws thereby to release the thread after the work-clamping means and 85 stitch-forming mechanism have been moved into stitching position.

15. In a sewing machine, the combination with stitch-forming mechanism, of work-clamping means situated above the 90 work, said stitch-forming mechanism and work-clamping means having a movement relative to each other in a direction parallel to the work held by the work-clamping means to effect a predetermined cycle of 95 operations including the stitching operation, and a thread-clamping device carried by the work-clamping means and actuated by said relative movement to clamp the thread at the end of the stitching operation. 100

16. In a sewing machine, the combination with stitch-forming mechanism, of work-clamping means situated above the work, said stitch-forming mechanism and work-clamping means having a movement 105 relative to each other in a direction parallel to the work held by the work-clamping means to effect a predetermined cycle of operations including the stitching operation, and a thread-clamping device carried 110 by the work-clamping means and actuated by said relative movement to clamp the thread at the end of the stitching operation and to release the thread during the formation of the initial stitches of the next suc- 115 ceeding stitching operation.

In testimony whereof, I have signed my name to this specification.

GLENN COLE.
